[21] Appl. No.: 772,425

[57] CLAIM

The ornamental design for an insulated portable food carrier, substantially shown and described.

DESCRIPTION

[22] Filed: Sep. 4, 1985

FIG. 1 is a perspective view of an insulated portable food carrier showing my new design;
FIG. 2 is a rear elevational view thereof;
FIG. 3 is a right side elevational view thereof, the opposite side being a mirror image; and,
FIG. 4 is a bottom plan view thereof.
